CLAIM

The ornamental design for a massage pad, as shown and described.

DESCRIPTION

FIG. 1 is a perspective view of a massage pad showing my new design;

FIG. 2 is a front view thereof;

FIG. 3 is a left side view thereof;

FIG. 4 is a top view thereof;

FIG. 5 is a bottom view thereof; and,

FIG. 6 is another perspective view of the massage pad shown in FIG. 1 in an environment as part of an inversion therapy table.

The broken lines seen in FIGS. 1-6 show portions of the massage pad that forms no part of the claimed design. The broken lines showing an inversion therapy table in FIG. 6 illustrate environment and form no part of the claimed design.

1 Claim, 4 Drawing Sheets
